Claims priority, application Great Britain Nov. 11, 1957

4 Claims. (Cl. 209—370)

This invention relates to plansifters used for classifying flour mill stock and particularly to the type of plansifter wherein a plurality of sieve units, each comprising a horizontal screen through which materials of less than a predetermined size can pass and a tray element on which the "throughs" from the screen are collected, both screen and tray being mounted in a framework having a plurality of vertical channels into which the classified materials can be directed in accordance with a predetermined scheme, are superimposed one upon another in an enclosed group in such a manner as to ensure that the vertical channels in the frame-works of adjacent sieve units coincide to form continuous channels through which classified materials or materials for classification can be transferred from a higher sieve unit to any lower sieve unit or to channels leading to outlet ports from the group enclosure.

In such plansifters clamping means are provided to hold the channel-forming sieve unit frameworks in close engagement with each other and with channel elements of the enclosure means so as to prevent the leakage of any material from its predetermined channel. It is essential that such clamping means be capable of preventing relative movement between any of the sieve units in a group and between any part of the group and associated enclosure members where damage to or wear on the engaging surfaces of the parts which form the channels could lead to the development of leakages. Further, in view of the continuous nature of the processes on which such machines are normally employed, it is desirable that the clamping means referred to shall be rapidly operable to permit sieve units to be freed for repair, rearrangement, or replacement in the shortest possible time. It is also desirable that such clamping and locking means shall be easily cleanable and shall not provide inaccessible pockets in the structure wherein material being processed can lodge and deteriorate to become a possible source of contamination or microbial infestation.

The object of this invention is to provide in plansifters of the type referred to, improved sieve unit clamping means having the desirable features described.

In accordance with this invention, each of a plurality of sieve units superimposed one upon another in a group contained within a box-like enclosure of substantially rectangular prismatic form having in one vertical side an access opening of such size as to permit of the group of sieve units being passed horizontally therethrough, and located at the corner extremities of each sieve unit in a leak-proof manner by vertical extensions of the walls of the enclosure, arranged so that sealed continuous channels which may be used as material transfer ducts are formed between the vertical outer faces of all the sieve units in the group and the vertical walls of the enclosure, is clamped laterally in its location means by clamping members which may serve all sieve units in a group and which are hingeably mounted on vertical pivots at the location extensions of the enclosure walls flanking the access opening and provided with pivotally mounted inter-

2

connecting tie-rods arranged so that when the tie-rod adjustment nuts are tightened pressure faces of the clamping members are brought to bear on adjacent corner extremities of the sieve unit in such a way as to hold it firmly in position, the pressure applied by the interconnected clamping members being equalized by a turning action of the associated members about the hinge and tie-rod pivots, which latter are arranged to provide that when tension is removed from the tie-rod assemblies they may be uncoupled from the clamping members which can then either be hinged clear of the access opening to afford unrestricted access to the sieve-units or be lifted vertically off their hinge pivots to facilitate cleaning operations.

Preferably all sieve units in a group located in the 15 manner described are clamped towards the base of the enclosure structure by clamping means comprising a supporting linkage pivotally mounted from the enclosure structure and arranged to hinge up or down under the control of a manually operable jack-screw element of the enclosure structure, and a clamping frame pivotally 20 suspended from the supporting linkage and arranged so that pressure applied to it by cam-surfaces of the said linkage are transmitted by leakage sealing extensions of the frame to the vertical walls of the channels formed in the sieve unit frameworks, the said clamping frame having ports and ducts whereby materials for processing passing through inlet spouts of the enclosure are transferred to the topmost sieve or to the vertical channels in the framework of the sieve units and also having rapidly removable 25 attachment means at its pivotal suspensions so that the complete frame may be quickly removed to facilitate cleaning.

The sieve unit corner extremities which engage the locating means described may have projecting surfaces 35 (which may be in the form of metal or other corner reinforcements) extending over the area of the sieve framework which contacts the leakproof seals of the location means so that except when a sieve unit is in position to be clamped it can be moved freely without risk of damage to the sealing means.

One form of the present invention is shown, by way of example, in the accompanying drawings, in which:

Figure 1 is a perspective view of a six-group plansifter with two doors for the access opening to one of the groups 45 and one door for another group removed to show the clamping members and tie-rod assemblies in clamping position.

Figure 2(a) is a perspective view to show the method 50 of locating and clamping a sieve unit in its enclosure structure.

Figure 2(b) shows one of the clamping members in the open position.

Figure 3 is an enlarged view of Figure 1 showing the 55 method of removing tie-rod assemblies and clamping members.

Figure 4 is a perspective view of part of one enclosure structure to show the means for clamping sieve units towards the base thereof.

Referring to Figure 1, the plansifter of basically known 60 form comprises a cabinet 1 housing six groups of sieve units 2. The cabinet 1 is suspended from roof members 3 by four sets of canes 4 and is caused to describe a gyratory motion by rotation of an eccentric weight (not shown) carried on a shaft 5 and driven by a motor 6 through belts 7. Stock to be sieved enters the top of the plansifter through ducts 8 and the sieved and classified stock leaves the bottom by the flexible ducts 9.

Three of the removable doors 10 are shown removed to expose the access openings through which the sieve 70 units may be removed and replaced.

Clamping means for each group of sieves is similar and that for one of the groups is shown in more detail

in Figures 2(a), 2(b) and 3. Each group is contained within a box-like enclosure 11 having in one side the access opening through which the sieve units 2 may pass horizontally. The units 2 are located in the enclosure 11 in a leak proof manner by vertical corner extensions 12 and 12a of the rear walls of the enclosure and by vertical extensions 13 of the side walls of the enclosure flanking the access opening. The units 2 are clamped laterally against the extensions 12a and between extensions 12 and 13 by two clamping members 14 which serve half the sieve units in the group and which are hingeably mounted on vertical pivots 15 carried by bracket extensions 15a of the extensions 13 flanking the access opening. The clamping members 14 are drawn together by two inter-connecting tie-rods 16 which pivotally engage claw members 17 on the clamping members 14 and are arranged so that when the tie-rods are tightened, pressure faces 18 of the clamping members 14 are brought to bear on the sieve units so as to hold them in position, the pressure applied by the clamping members 14 being equalised by a turning action about the hinge and tie-rod pivots. When the tie-rods 16 are slackened they may be uncoupled from the clamping members 14 which can then either be hinged clear of the access opening as shown in Figure 2(b), to afford unrestricted access to the sieve units or be lifted vertically off the hinge pivots 15, as shown in Figure 3, to facilitate cleaning operations.

Vertical channels indicated at X are formed by the sieve units, some within the units and some between the units and the enclosure. To assist in making each channel of the channels between the units and the enclosure proof against leakage the vertical extensions 12, 12a and 13 are provided over the whole of their sieve-engaging surfaces with strips of resilient material 37 and 38 which, when the units are clamped in position, are compressed between the associated extensions and the engaging surfaces of the units thus providing leakproof joints between the units and the extensions. To avoid damaging these seals when removing or replacing sieve units the corners of the units which engage the seals have projecting surfaces in the form of metal reinforcements 19. Thus except when a sieve unit is in position to be clamped it can be moved freely without risk of damage to the leak-proof sealing.

Referring to Figure 4, all the sieve units in a group, after being clamped laterally as already described, are clamped towards the base of the plansifter by a clamping means comprising a supporting linkage 20, arcuate-ended extensions 39 of which are housed in a channel-shaped member 40 of the enclosure 11 in such a way that upper and lower peripheral extremities of the said arcuate-ended extensions in association with the upper and lower webs of the said channel-shaped member provide floating pivot means about which the said linkage is arranged to hinge vertically under the control of a manually operated jack-screw 21 which is axially fixed but freely rotatable in pivoting crossbar 21a of the supporting linkage, the said jack-screw being in screwed association with a threaded member 22 secured to the top plate 23 which forms a fixed part of the enclosure. The clamping means also comprises a clamping frame 24 freely suspended on two screwed members 41 from tapped extensions 42 of the supporting linkage 20 and arranged so that when the linkage 20 is pivoted downwards by the screwing-in of the jack-screw 21, the clamping frame 24 is lowered into association with the top sieve unit and thereafter pressure applied to it by pressure surfaces 25 on linkages 20 are transmitted by leakage sealing extensions 26 to the vertical walls of the channels X formed in the sieve units 2. The clamping frame has ports 27 and ducts within it so that stock for processing passing through inlet spouts of the enclosure is transferred to the screen 2s of topmost sieve unit and/or to vertical channels in the sieve group.

The screwed members 41 are provided with sealing pads 43 which are retained in position by springs 44 to prevent material leakage by way of the holes in the clamping frame through which the screwed members pass.

Removal of the clamping frame 24 and the supporting linkage 20 from the enclosure 11 for cleaning purposes is effected by unscrewing the two screwed members 41 so that the clamping frame can be disengaged 10 and lowered away from the linkage which can then be disconnected from the jack-screw 21 and drawn clear of the locating channel member 40.

What is claimed is:

1. A plansifter comprising a plurality of sieve units 15 superimposed one upon another in a group contained within a rectangular box-like enclosure having in one vertical side an access opening to permit of the group sieve units being passed horizontally therethrough, said sieve units being clamped laterally by clamping members 20 which may serve all sieve units in a group and which are hingeably mounted on vertical pivots at the enclosure walls flanking the access opening and provided with pivotally mounted interconnecting tie-rods, tightening means for said tie-rods arranged so that when tightened pressure faces of the clamping members are brought to bear on adjacent corner extremities of the sieve units in such a way as to hold them firmly in place, the pressure applied by the interconnected clamping members being equalised by a turning action of the associated members 30 about the hinge and tie-rod pivots, which latter are arranged to provide that when tension is removed from the tie-rods they may be uncoupled from the clamping members which can then either be hinged clear of the access opening to afford unrestricted access to the sieve 35 units or be lifted vertically off their ringe pivots to facilitate cleaning.

2. A plansifter as claimed in claim 1 wherein the sieve units are located in the enclosure by vertical extensions of the walls of the enclosure arranged with leak proof 40 seals consisting of strips of resilient material covering the whole surface of those parts of the said extensions which engage the sieve units so that sealed continuous channels which may be used as material transfer ducts, are formed between the vertical outer faces of all the 45 sieve units in the group and the vertical walls of the enclosure.

3. A plansifter as claimed in claim 2 wherein all sieve units in a group are clamped towards the base of the enclosure by clamping means comprising a supporting linkage 50 pivotally mounted from the enclosure and arranged to hinge up or down under the control of a manually operable jack-screw supported in the top of the enclosure, and a clamping frame freely suspended from the supporting linkage and arranged so that pressure applied to it by 55 cam surfaces of said linkage are transmitted by leakage sealing extensions of the frame to the vertical walls of channels formed in and by the sieve unit frameworks, said clamping member having ports and ducts whereby material for processing is transferred to the topmost sieve 60 unit or to the vertical channels and also having removable attachment means at its points of suspension so that the complete frame may be quickly removed to facilitate cleaning.

4. A plansifter as claimed in claim 2 wherein the sieve 65 unit corner extremities which engage the locating means formed by the vertical extensions of the walls of the enclosure and their associated leak-proof seals, have projecting surfaces extending over the area of the sieve unit which contacts the said leakproof seals so that except when 70 a sieve unit is in position to be clamped it can be moved freely without risk of damage to the seals.
